UNITED STATES PATENT OFFICE.

JAMES H. BARLOW, OF LEWISTON, MAINE, ASSIGNOR TO CROMPTON & KNOWLES LOOM WORKS, OF WORCESTER, MASSACHUSETTS, A CORPORATION OF MASSACHUSETTS.

JACQUARD LOOM.

1,323,437.

Specification of Letters Patent.

Patented Dec. 2, 1919.

Application filed June 3, 1919. Serial No. 301,452.

To all whom it may concern:

Be it known that I, JAMES H. BARLOW, a citizen of the United States, residing at Lewiston, in the county of Androscoggin 5 and State of Maine, have invented a new and useful Jacquard Loom, of which the following is a specification.

This invention relates to a Jacquard loom provided with reversible card feeding mechanism, and also to drop-box mechanism controlled by card perforations. It is essential that the indication for a drop-box change be made on the pick previous to the actual box movement. This indication is commonly made by a special set of jacquard needles, controlled by special perforations in the pattern card, and the indication for a box change is commonly made from the card preceding the card which is to be in operative position when the change actually occurs.

No difficulty is encountered with this arrangement so long as the card chain runs in a single direction only, but when the chain is reversed, the box change indications are found in the card following that on which the change should occur, instead of in the card preceding the change.

The object of my invention is to provide an improved construction by which the drop-box change may be correctly indicated with the pattern chain feeding either forward or backward.

With this general object in view, an important feature of my invention relates to the provision of two sets of box change indicating perforations in the pattern card, together with devices coöperating with one set when the chain is feeding forward, and with the other set when the chain is feeding backward. My invention further consists in the provision of mechanism by which a change in the direction of card feed causes a corresponding change in the operation of said devices.

In the preferred embodiment of my invention two sets of jacquard needles are provided, corresponding to the two sets of card perforations, and one set of needles is operative during forward card movement, and the second set during backward card movement.

My invention further consists in arrangements and combinations of parts which will be hereinafter described and more particularly pointed out in the appended claims. 55

A preferred form of my invention is shown in the drawings in which—

Figure 1 is a front elevation of a portion of a jacquard mechanism embodying my improvement; 60

Fig. 2 is an enlarged detail view of certain parts, and

Fig. 3 is a plan view of a portion of a card chain. 65

Referring to the drawings, Fig. 1 shows a jacquard frame 10 having the usual griff bars 11 vertically movable by lifting rods 12 and 13 alternately actuated by the driving mechanism (not shown). The usual pattern chain cylinder 14 is mounted on rods 15 by which it is horizontally reciprocated. As it moves to the left it operates through the jacquard needles to move all of the uncalled hooks from the path of the ascending griff 70 bars and as it moves to the right it is engaged by one of the feed pawls 16 or 17 and is rotated one quarter of a revolution forward or backward as the case may be. 75

The pawls 16 and 17 are connected by a link 18 and the pawl 17 is extended to the left beyond its bearing and is connected by a link or cord 19 to a reversing lever 20. The reversing lever is controlled by a pattern chain 21 forming part of a reversing 80 mechanism which constitutes no part of my invention, and which is fully described in prior United States Patent No. 578,068. When a ball or raised link comes under the lever 20, the feed pawl 17 becomes operative, 85 and the feed pawl 16 becomes simultaneously inoperative. 90

The drop-boxes (not shown) are controlled by cords or links 22, angle-levers 23, and cords or links 24 connected to jacquard hooks 25. Two sets of hooks are provided, one set being under the control of the upper jacquard needles 26, and the other set being controlled by the lower jacquard needles 27. 95

A portion of a pattern card chain is shown 100 in Fig. 3, including a succession of cards 28, 29 and 30. When the chain is running in the direction of the arrow *a* in Fig. 3 a drop-box change occurring when the card 28 is in

operative position is indicated by a perforation 31 in the preceding card 29. When the chain is reversed and is running in the direction of the arrow *b* in Fig. 3, the indication for the same change comes from the perforation 32 in the card 30 instead of from the perforation 31 in the card 29.

I will now describe the arrangement by which the perforation 31 becomes inoperative, and the perforation 32 becomes operative upon the reversal of card feed.

The needles 26 and 27 previously described are connected to arms 33 and 34 secured to a short shaft 35 or otherwise rotatably mounted upon a fixed axis. A third arm 36 is secured to the shaft 35 and is connected by a cord or link 37 to the reversing lever 20. A fourth arm 38 may be provided on the shaft 35, to which a coiled spring 39 is connected to yieldingly hold the shaft in the position shown in Fig. 1.

The needles 26 and 27 are provided with slots 40 permitting lost motion between the needles and the arms 33 and 34, and are also provided with compression springs 41 engaged at their left hand ends by fixed cross rods 42, and at their right hand ends engaging off-set portions of the needles.

The springs 41 normally press the needles yieldingly to the right to engage the pattern card on the member 14. When the arms 33 and 34 are positioned as shown in Figs. 1 and 2, the upper needles 26 are withdrawn from operative position, and all of the jacquard hooks controlled thereby are also held in inoperative position. At the same time the lower needles 27 are released by the arms 34 and are yieldingly moved to operative position by their springs 41.

When a needle is engaged by a pattern card, the slot 40 in the needle permits it to be moved to the left, withdrawing its hook from the path of the griff bar. When a needle encounters a perforation in the card, the needle remains in operative position and its hook is lifted by the griff bar to cause a box change to be indicated.

Reference to Fig. 3 will show that the perforations 31 and perforations 32 are positioned in different portions of the card, so that a perforation 31 can never cause indication by a needle 26 and a perforation 32 can never cause indication by a needle 27.

As the lever arms 33 and 34 are controlled from the reversing lever 20, a change in the position of the reversing lever will withdraw one set of needles from operative position and will simultaneously advance the second set to operative position. I am thus able to provide operative indicating perforations in the card preceding a drop-box change with the pattern chain moving in either direction, and such operative perforations become inoperative as soon as the di-

rection of pattern feed is reversed, other perforations then becoming operative.

I thus accomplish my desired result, namely, the correct control of the drop-box changes from a pattern chain moving in either direction.

Having thus described my invention, it will be evident that changes and modifications can be made therein by those skilled in the art without departing from the spirit and scope thereof as set forth in the claims, and I do not wish to be otherwise limited to the details herein disclosed, but what I do claims is:—

1. In a loom, the combination of a jacquard mechanism including a plurality of pattern cards, means to feed said cards in opposite directions, drop-box mechanism controlled from said cards, and means to indicate a certain box change upon a certain card when feeding in one direction, and upon a different card when feeding in the opposite direction.

2. In a loom, in combination, a jacquard mechanism including a plurality of pattern cards, means to feed said cards in opposite directions, drop-box mechanism, a set of needles controlling the box changes when the cards are fed in one direction, and another set of needles controlling the box changes when the cards are fed in the opposite direction, said cards having a separate set of perforations for each set of needles.

3. In a loom, in combination, a jacquard mechanism including a plurality of pattern cards, means to feed said cards in opposite directions, drop-box mechanism, a set of needles controlling the box changes when the cards are fed in one direction, another set of needles controlling the box changes when the cards are fed in the opposite direction, said cards having a separate set of perforations for each set of needles, and means to render one set of needles operative and the other inoperative when the direction of card feed is reversed.

4. In a loom, in combination, a jacquard mechanism including a plurality of pattern cards, means to feed said cards in opposite directions, drop-box mechanism, a set of needles controlling the box changes when the cards are fed in one direction, another set of needles controlling the box changes when the cards are fed in the opposite direction, said cards having a separate set of perforations for each set of needles, and means to withdraw one set of needles and to advance the other set of needles when the direction of card feed is reversed.

5. In a loom, in combination, a jacquard mechanism including a plurality of pattern cards, means to feed said cards in opposite directions, drop-box mechanism, a set of needles controlling the box changes when the

cards are fed in one direction, another set of needles controlling the box changes when the cards are fed in the opposite direction, said cards having a separate set of perforations for each set of needles, and means to withdraw one set of needles and to advance the other set of needles when the direction of card feed is reversed, said needles having a lost-motion connection with said latter

10 means.

6. In a loom, the combination of a jacquard mechanism including a plurality of pattern cards, means to feed said cards in opposite directions, drop-box mechanism, 15 and means to control the box changes by card perforations, said cards having perforations in a certain portion thereof effective to control the box changes when fed in one direction, and having perforations in a

different portion thereof effective to control the box changes when fed in the opposite direction.

7. In a loom, a jacquard mechanism comprising a card cylinder, a pair of feed pawls effective to feed said cylinder in opposite directions, a reversing lever controlling the position of said pawls, a pattern chain positioning said lever, drop-box mechanism, two sets of needles controlling the box changes, and connections from said needles to said reversing lever through which one set of needles is advanced to operative position and the other set is withdrawn to inoperative position, as the position of the feed pawls is changed by said reversing lever.

In testimony whereof I have hereunto affixed my signature.

JAMES H. BARLOW.
